UNITED STATES PATENT OFFICE.

LEWIS G. MCCLINTOCK, OF PITTSBURGH, PENNSYLVANIA, ASSIGNEE TO PITTSBURGH
TRANSFORMER COMPANY, A CORPORATION OF PENNSYLVANIA.

TRANSFORMER TANK.

Specification of Letters Patent. Patented Feb. 28, 1922.

1,408,215.

Application filed November 6, 1920. Serial No. 422,467.

To all whom it may concern:

Be it known that I, LEWIS G. MCCLINTOCK, a citizen of the United States, residing at Pittsburgh, in the county of Allegheny and State of Pennsylvania, have invented certain new and useful Improvements in Transformer Tanks, of which the following is a specification.

This invention relates to tanks and particularly to corrugated tanks, for instance for oil cooled transformers in which the tank body is deeply corrugated to give a relatively large cooling surface for the oil. In such tanks, when made of sheet metal and when the corrugations exceed a certain depth, there is a tendency for the pressure of the contained oil to cause a bulging or warping of the corrugations destroying their symmetry and sometimes interfering with their cooling effect.

The chief object of this invention is to provide a tank in which the corrugations will be reinforced in simple and inexpensive manner permanently sustaining the corrugations in their original shape without impeding the cooling effect and without detracting from the regular symmetrical appearance of the tank.

In the accompanying drawings illustrating the invention,

Fig. 1 is a horizontal sectional view on line 1-1 of Fig. 2 of a large transformer tank illustrating one embodiment of the invention, and

Fig. 2 is a vertical sectional view of the same on line 2-2 of Fig. 1.

In the embodiment of the invention illustrated in the drawings a tank having a top flange T and bottom M has its body B deeply corrugated. The corrugations C have their outer bends at 5 and their inner bends at 6 and between these the sides 7 of the corrugations extend as substantially plane surfaces zig-zagging at angles to each other. The tops 8 and bottoms 9 of the corrugations are closed over in arch form and the corrugations overhang the top and bottom of the tank and there are continuous air spaces extending between the corrugations from top to bottom. Retaining hoops or bands 10 surround the body of the tank tightly encircling the outer bends of 5 of the corrugations and preferably welded thereto to rigidly space these bends

Between adjacent sides 7 of the corruga-

tions are spacer members 12 held in an intermediate position between the bends 5 and 6 and in the specific example shown these members are hollow pipes extending substantially throughout the length of the corrugations. At certain of the bands 10 each pipe is provided with arms 13 welded to the pipe and adjustably bolted to mating arms 14 extending inward from the bands.

The spacers 12 are thus held permanently positioned against shifting between the wedging surfaces of the corrugations. These pipe spacers form substantially no obstruction to the circulation of the cooling air between the corrugations. They are themselves of heat conducting material and being hollow provide a vertical ventilating passage through their interior. At the same time they have extended contact with the sides of the corrugations and rigidly support these sides against bulging or warping in service.

The pipe spacers are easily formed by simply cutting off standard stock to proper length and they may be applied to any tank by inserting them endwise in the outer position of the space between corrugations and then pressing them inward when properly positioned, finally bolting them in their innermost position. Where the spaces between the corrugations is narrower as at 17 (Fig. 1) a smaller pipe may be substituted or the same size pipe may be used slightly flattened as shown. The invention is easily adaptable to various tanks and its application is simple and inexpensive, the spacers intervening in even symmetrical manner between the corrugations.

I claim:-

1. The combination of a tank having corrugated sheet metal sides forming a series of outwardly projecting vertical corrugations, and a series of vertical spacing members between the sides of the corrugations, said spacing members forming with the sides of the corrugations a series of channels for the upward flow of currents of air.

2. The combination of a tank having corrugated sheet metal sides forming a series of outwardly projecting vertical corrugations, a series of vertical spacing members between the sides of the corrugations, said spacing members forming with the sides of the corrugations a series of channels for the upward flow of currents of air, and a re-

taining band transversely supported across the ends of said corrugations.

3. The combination of a tank having corrugated sheet metal sides forming a series 5 of outwardly projecting vertical corrugations, a series of vertical spacing members between the sides of the corrugations, said spacing members forming with the sides of the corrugations a series of channels for the upward flow of currents of air, and a retaining band transversely supported across the ends of said corrugations and itself supporting the spacing members.
4. The combination of a tank having corrugated sheet metal sides forming a series of outwardly projecting vertical corrugations, and a series of vertically extending pipes held in place against the sides of adjacent corrugations.
5. The combination of a tank having corrugated sheet metal sides forming a circumferentially arranged series of radially projecting corrugations, a circumferential retaining band around the ends of said cor-

rugations transverse thereto, and a series of 25 spacing members between the several corrugations parallel thereto and supported by the retaining band.

6. The combination of a tank having corrugated sheet metal sides forming a series 30 of outwardly projecting vertical corrugations, a series of vertically extending pipes held in place against the sides of adjacent corrugations, and a retaining band transversely supported across the ends of the corrugations and itself supporting the pipes.

7. The combination of a tank having corrugated sheet metal sides forming a series 35 of outwardly projecting vertical corrugations, a series of vertically extending pipes held in place against the sides of adjacent corrugations, a retaining band transversely supported across the ends of the corrugations, and adjustable supports carried by said retaining band and supporting the pipes.

LEWIS G. McCLINTOCK.
